UNITED STATES PATENT OFFICE.

LOUIS SCHUTTE, OF PHILADELPHIA, PENNSYLVANIA.

STEAM-BOILER.

SPECIFICATION forming part of Letters Patent No. 291,092, dated January 1, 1884.

Application filed May 10, 1883. (No model.)

To all whom it may concern:

Be it known that I, LOUIS SCHUTTE, of Philadelphia, in the county of Philadelphia and State of Pennsylvania, have invented certain 5 Improvements in Steam-Boilers, of which the following is a specification.

My invention relates to improvements which, although adapted to some extent for general application, are mainly applicable to what are 10 known in the art as "sectional water-tube boilers," of which the boiler represented in the annexed drawings is a type.

The improvements have reference to end 15 fittings or connections for the tubes, constructed in a peculiar manner to permit ready access to the interior of the tubes or flues for the purpose of removing obstructions therefrom.

It also consists in a superheater and connections therefor constructed in such manner 20 that said superheater may be used either as a superheater or as a portion of the steam-generating apparatus.

The improvement further consists in plates 25 of peculiar construction to form the exterior jacket or casing of the boiler.

Referring to the accompanying drawings, Figure 1 represents a sectional elevation of a boiler with my improvements embodied therein. Fig. 2 is an inside front view of one of the 30 plates used to inclose the boiler. Fig. 3 is a transverse section through the plate and its covering. Fig. 4 is an enlarged section of details of the tube and connections.

Referring to the drawings, A represents the 35 boiler proper, consisting of a series of inclined tubes, B, furnished at the end with caps or fittings C, screwed thereon, the tubes being arranged in vertical series with the caps or fittings at each end of the series connected by 40 short tubes D of reduced diameter, threaded in reverse directions at their opposite ends, as shown in Fig. 4. The lowermost connecting-tube, B, at the rear end of each section or series, connects with a mud-drum, E, while 45 the uppermost connecting-tube at the forward end communicates with the interior of the manifold F, which latter is in turn connected to a drum or series of drums, H, the rear ends of the drums being connected to the mud-drum 50 E by a down-pipe or series of down-pipes, I. It will be seen that under this arrangement the water may make a complete circuit ver-

tically of the boiler, the heated water rising from the mud-drum through the caps C and vertical pipes D at the rear end, and thence 55 upward through the inclined pipes B to the front of the generator, where it ascends through the forward caps and pipes, D, into the drum H, from which it returns through the down-pipes I into the mud-drum. The drum H is 60 connected at its upper rear end with an elevated steam-drum, K, from which the steam is 65 conveyed to the engine or apparatus in which it is to be used, either directly or after first passing through the superheater.

The superheater herein shown consists in the two inclined tubes S and T, joined at their rear ends. The lower pipe, T, is connected by a pipe, x, with the steam-discharge pipe M, leading from the steam-drum K. The pipe x 70 is provided, as shown, with a valve, O, near its upper end, by which communication with the steam-pipe may be closed. The steam-pipe is also provided with a valve, N, by which it may be closed between the drum K and the 75 pipe x. The upper tube, S, of the superheater is connected by a pipe, y, with the steam-drum K. When the valve N is closed and the valve O opened, the steam is compelled to pass from the drum K downward through the pipe y, 80 and thence through the superheater, escaping finally through the pipe x into the discharge-pipe M.

Owing to the fact that the superheater is located in the base of the furnace and exposed 85 directly to the action of the fire, the steam is thoroughly superheated in its passage, and consequently delivered in a dry condition.

In order to adapt the superheater to be used when required as a portion of the steam-generating apparatus, a pipe, W, is extended 90 from the lower end of the pipe x to the mud-drum E, and provided with the cock or valve Q, by which it may be closed. If the valve O be closed and the valves N and Q be opened, 95 the circulation will be from the mud-drum through pipe W into the superheater, and thence through the pipe y into the steam-drum, any water which may be carried with the steam through the pipe y into the drum 100 K flowing therefrom into the lower drum, H, and returning thence through the down-pipes I to the mud-drum.

At the foot of the pipe x an outlet-valve, P,

is applied, for the purpose of discharging the water from the superheater, when required, and of observing the quality or dryness of the steam.

5 In order that access may be had to the base of the boiler for the purpose of observing the interior condition of the tubes and of removing obstructions therefrom, it is desirable that the lowermost tube, B, of each generator-section shall be provided with a readily-removable cover. To this end I adopt the construction represented in Figs. 1 and 4. The cap C at the end of the lower tube is provided with a front opening, a, closed by means of a cap or plug, b, held in place by an outside pressure-screw, c, seated in a removable bar or plate, d, this bar being loosely and removably seated in a jaw or pocket formed on the outside of the cap C. By turning the screw backward, the plate d may be relieved from pressure, whereupon said plate, together with the plate b and its screw, may be lifted out of the pocket, thereby leaving the opening a exposed in such manner as to permit the introduction of a rod, scraper, or other instrument into the end of the tube.

To secure a proper closing of the opening a it is advisable to make the same of as small diameter as allowable. It is therefore made, 30 as shown in the drawings, of a diameter less than that of the tube B, and placed with its axis below that of the tube, in order that the rod or other tool inserted through it may act on the lower surface of the tube. The essential feature of the invention in this regard consists in the employment of a removable cap, a screw, and a screw-supporting plate, and it is manifest that they may be varied in form and detail without essentially changing their 40 action or departing from the mode of operation.

For the purpose of permitting the introduction of a scraper or other instrument through the cap C and vertical connecting-tubes D, the cap at the lower end of each series is provided with an opening in the under side, closed by means of a vertical screw-plug, R, which may be removed at will.

For the purpose of inclosing the generator proper, I provide a suitable frame-work or support, which may be of any ordinary form or construction, with duplicate covering-plates G, such as represented in Figs. 1, 2, and 3. Each consists of a flat plate or body portion, having its two faces provided with projecting flanges or ribs g, extending around the same at a short distance from the outer edge. Each plate has one face covered and protected within the line of the flange by a body of non-conducting material secured in place by means of the surrounding flange and of plates or anchors h, made of any suitable form, and secured to the face of the plate by means of rivets, bolts, or screws. The form of these anchors h is not material, provided they are adapted to lock firmly with the non-conducting material applied over and around them,

so as to retain the same firmly in place. Each plate is provided on one side, around or outside of its flange g, with a narrow strip of refractory packing material, i.

The plates are applied in position, as represented in Fig. 1, one above another, with their edges overlapping each other, the packing material applied, as described, serving to 75 protect their entire inner surface against the action of the heat and flames.

The present invention is restricted to those matters and things hereinafter claimed, and as to all matters which may be described or 80 shown, but which are not claimed, the right is reserved to make the same the subject of a separate application.

Having thus described my invention, what I claim is—

1. In combination with the water-tube, its cap or fitting C, provided with the opening a, and having the pocket or receptacle cast integral therewith, the valve b, plate d, and screw c.
2. The cap or fitting C, cast complete in one 90 piece, with the opening a, to afford access to the tube, and with the external pocket to admit the valve and valve-supporting devices.
3. In combination with the tube B, the cap or fitting C, provided with an opening, a, having a diameter less than that of the tube, and arranged with its axis below that of the tube, and means, substantially as described, for closing said opening, whereby the introduction of a tool upon the lower surface of the tube is 100 permitted.
4. In combination with the tubular boiler, having the mud-drum at the base and the steam-drum at the top, the superheater, the steam-discharge pipe from the steam-drum, 105 and provided with a closing-valve, a pipe connecting the steam-drum with the superheater, a second pipe provided with a closing-valve, connecting the superheater with the steam-discharge pipe, and a third pipe provided with a 110 closing-valve, connecting the superheater with the mud-drum, whereby the superheater may be used as a portion of the generating apparatus at will.
5. The combinations of the tubes B, and the 115 vertical connections at their ends, communicating-drums H and K, pipe I, mud-drum E, the superheater-pipes x, y, and W, and the valves Q, N, and O.
6. The improved plate for a boiler-casing, 120 consisting of the flat body portion, having the ribs g, formed on its two surfaces, combined with the anchors h, and the body of refractory or non-conducting material applied to one face of the plate within the flange.
7. The combination of the plates flanged upon both faces, the body of refractory material applied to one surface within the flange, and the body of refractory material applied to one face outside of said flange.

LOUIS SCHUTTE.
